United States Patent Office.

JOHN JOS. LAHAYE AND S. T. REEVES, OF READING, PENNSYLVANIA.

Letters Patent No. 60,748, dated January 1, 1867.

IMPROVEMENT IN SLIDE VALVES.

The Schedule referred to in these Letters Patent and making part of the same.

TO ALL WHOM IT MAY CONCERN:

Be it known that we, J. J. LAHAYE and S. T. REEVES, of Reading, Berks county, Pennsylvania, have invented certain improvements in Slide Valves; and we do hereby declare the following to be a full, clear, and exact description of the same, reference being had to the accompanying drawing, and to the letters of reference marked thereon.

Our invention consists in the arrangement of a valve having a recess containing an elastic material, with a plate having a rib which projects into the said recess, as fully described hereafter, so that the said elastic material shall act as a spring to maintain the valve against its seat, and as a packing to prevent the passage of steam between the ribbed plate and the valve.

In order to enable others skilled in the art to make and use our invention, we will now proceed to describe its construction and operation.

On reference to the accompanying drawing, which forms a part of this specification—

Figure 1 is a sectional elevation of a valve-chest and slide valve with our improvements.

Figure 2 is a plan view of part of the valve; and

Figure 3, an inverted plan view of another part of the valve.

Similar letters refer to similar parts throughout the several views.

A is a valve-chest in which slides a valve, B, of the ordinary construction, the latter being connected to the usual spindle, C, which passes through a stuffing-box in front of the valve-chest. To the top of the valve is secured a plate, a, in which is an annular recess, x, (fig. 2,) and in the latter is fitted a ring, c, of gum, cork, or other elastic packing material. Into the recess, x, projects an annular rib, e, on a plate, D, the upper face of which bears against a steel plate, E, secured to the under face of the valve-chest cover, F. In the plate, D, is a circular opening, y, and in the plate, E, and in the chest cover above it, is an opening, f. The elastic material in the recess, x, serves as a spring to force the valve and the plate D apart from each other, so that the valve is caused to bear on its seat, while the plate D is maintained tightly against the plate E. It will be seen that while the two plates are thus separated the elastic material is compressed within the recess, and is caused to bear firmly against the sides of the latter, and against the rib, e, so as to act as a packing, which prevents the escape of steam from the chest, between the plates a and D. Should either of the plates, D or E, become so worn as to permit the passage of steam between them, it will escape through the opening, f, from the chest, so that any pressure upon the top of the valve, other than that of the atmosphere is prevented. It will be apparent that the recesses, x, and the rib, e, may be of any desired form.

We claim the arrangement of the valve B, with its recess containing an elastic packing material, and the plate D, with its rib, e, substantially as and for the purpose described.

In testimony whereof we have signed our names to this specification in the presence of two subscribing witnesses.

JOHN JOS. LAHAYE,
S. T. REEVES.
